UNITED STATES PATENT OFFICE

WILLIAM GRANT, OF SHEFFIELD, ENGLAND

KNIFE BLADE

Application filed February 6, 1930, Serial No. 426,409, and in Great Britain February 16, 1929.

This invention relates to knife blades of the type in which a series of grooves is ground in one or both of the blade surfaces adjacent to the cutting edge, the object of the invention being to provide an improved formation of cutting edge which is particularly applicable for use in cutting tomatoes, fruit and the like, although the invention may be applied with advantage in other circumstances.

10 Knife blades are known with closely arranged grooves of a narrow V-section producing a series of points on the blade edge and it has been proposed to make the grooves of a rounded outline and of a semi-circular section in one or both surfaces of the blade, but such rounded grooves have been separated by substantial lengths of the original edge and all the known forms of grooves have been made to become gradually deeper towards the cutting edge to intersect that edge and thus to form notches therein. According to the present invention, however, the grooves are in the form of rounded depressions having rounded outlines disposed in close proximity to one another and meeting the cutting edge of the blade without intersecting it so that the edge retains its original shape. This may be effected by making each of the groove depressions to become gradually shallower

20 towards the cutting edge, preferably so that a part of the base of the depression is substantially parallel to the opposite surface of the blade adjacent to the edge.

In the accompanying drawing:-

25 Figure 1 is an elevation of a knife according to the present invention.

Figure 2 is an elevation on an enlarged scale of part of a blade illustrating a slight modification.

30 Figure 3 is a transverse section, exaggerating the thickness for the sake of clearness, on the line 3-3 of Figure 2, and

Figure 4 is a fragmentary view looking at the edge of the blade.

35 Like reference numerals indicate like parts throughout the drawing.

In carrying out the present invention a knife blade 6 is first ground to a normal cutting edge 7 having no substantial thickness and of the usual straight line or curve de-

termined by the general shape of the blade. A series of grooves in the form of rounded depressions 8 is then ground in one or both of the blade surfaces to meet the edge 7 without intersecting it. As shown in the drawing each of the groove depressions 8 is of a rounded outline extending from the cutting edge 7 and the surface enclosed by the outline is also of a rounded shape. The groove depressions 8 are preferably formed by means of a grinding disc or wheel having a rounded operative edge. Although various sizes of grinding discs may be used the preferred size has a diameter of about three or four inches and a thickness of about half an inch to three-quarters of an inch, its edge being approximately semi-circular in transverse section.

In order that the groove depressions 8 may meet the edge 7 without intersecting it they are each made to become gradually shallower towards the edge 7 as shown in Figure 3. The central portion of the base of this shallowing part of the depression is thus at a more acute angle with the opposite surface of the blade than the one in which it is ground, and is preferably substantially parallel to the opposite surface adjacent to the edge as shown in Figure 3.

It is preferred to provide the groove depressions 8 alternately in both surfaces of the blade as illustrated, those in one surface being situated between those in the other surface. If desired, however, they may all be formed in one surface.

As the groove depressions 8 are made to meet the cutting edge 7 without intersecting it as illustrated, this edge will retain its shape, but where each groove depression meets it, preferably as a chord of a semi-circle as illustrated, there will be a region of thinner metal adjacent to the cutting edge producing a razor-like edge, whilst between the groove depressions the normal blade structure will provide the necessary strength and support. The groove depressions are disposed in close proximity to one another in one or both surfaces and may be practically contiguous as illustrated in Figure 1, or they may be separated by relatively short un-grooved portions 9 of the blade as illustrated

in Figure 2 to increase the portion of normal blade structure strengthening and supporting the razor edge produced by the formation of the groove depressions 8.

5 To obtain the best results from the present invention the size of the groove depressions 8 is an important factor. If they are too small there is a danger of producing a jagged saw-like edge, whilst if they are too 10 large there will be insufficient support given to the central portions of the razor-like cutting edge produced by the groove depressions. In the preferred form and size the width of the depression is a maximum at the cutting 15 edge and this width is approximately a quarter of an inch, so that when the groove depressions are formed in both surfaces of the blade the centre of one is separated from the centre of the next one in the same surface by approximately half an inch. This 20 distance will, however, be slightly increased when adjacent groove depressions are separated by short ungrooved portions 9. The dimensions given may, however, be considerably varied without departing from the 25 invention.

What I claim is:—

1. A knife blade having a series of depressions in its surface adjacent to the cutting 30 edge and meeting that edge without intersecting it, substantially as specified.

2. A knife blade having a series of rounded depressions having rounded outlines in its surface disposed in close proximity to one 35 another and meeting the cutting edge of the blade without intersecting it, substantially as specified.

3. A knife blade having a series of rounded depressions having rounded outlines alternately disposed in the two surfaces of the 40 blade in close proximity to one another and meeting the cutting edge of the blade without intersecting it, substantially as specified.

4. A knife blade having a series of depressions in its surface formed to become gradually shallower towards the cutting edge and to meet that edge without intersecting it, substantially as specified.

5. A knife blade having a series of depressions in its surface meeting the cutting edge 50 without intersecting it and having the central portion of the base of each depression at a more acute angle with the opposite surface of the blade than the one in which it is formed, substantially as specified.

6. A knife blade having a series of depressions in its surface formed to become gradually shallower towards the cutting edge to meet that edge without intersecting it and 60 with the base of such shallowing part substantially parallel to the opposite surface of the blade adjacent to the edge, substantially as specified.

7. A knife blade having a series of rounded 65 ed depressions having rounded outlines dis-

posed in close proximity to one another alternately in the two surfaces of the blade, each depression being formed to become gradually shallower towards the cutting edge to meet that edge without intersecting it and 70 with the base of such shallowing part substantially parallel to the opposite surface of the blade adjacent to the edge, substantially as specified.

In testimony whereof I hereunto affix my 75 signature.

WILLIAM GRANT.
